UNITED STATES PATENT OFFICE.

MILLER REESE HUTCHISON, OF WEST ORANGE, NEW JERSEY, ASSIGNOR TO LOVELL-McCONNELL MANUFACTURING COMPANY, A CORPORATION OF DELAWARE.

DIAPHRAGM-HORN.

1,148,686.

Specification of Letters Patent.

Patented Aug. 3, 1915.

Application filed May 11, 1911. Serial No. 626,488.

To all whom it may concern:

Be it known that I, MILLER REESE HUTCHISON, a citizen of the United States, and resident of West Orange, in the county of Essex and State of New Jersey, have invented certain new and useful Improvements in Diaphragm-Horns, of which the following is a specification.

This invention relates to mechanically actuated diaphragm horns particularly to those of the class in which the diaphragm is vibrated bodily by high speed mechanism, such as a shaft or other rotary member driven by an electric motor and provided with an eccentric portion or projections adapted to transform rotary motion into vibratory movement. In my co-pending application, Serial No. 626,487, filed May 11, 1911, I have described various useful features of design and operation for more or less tempering or cushioning the application of power to the diaphragm, particularly by means of various forms and arrangements of cushioning members for partially absorbing and partially transmitting the efforts exerted by the rotary driver.

My present invention relates to certain forms of signal wherein the cushioning or yielding actuating member is carried by the rotary driving member. Preferably such cushioning or yielding member is arranged so that it is caused to yield under the normal effort exerted by the driver in actuating the diaphragm, so that it yields at each driving contact.

A simple embodiment of my invention is one in which a rigidly mounted rotary driver is provided with a projection of spring material, which may be secured rigidly to the rotary part and preferably contacts with the diaphragm or a wear piece thereon, the projection being of such flexibility relative to the diaphragm as to yield to a suitable degree at each driving contact. While the spring projections may be constructed in a variety of ways, it is preferable to make them in the nature of thin spring teeth projecting freely from the rotary member, preferably from the periphery thereof, their inner ends being secured rigidly to the body of the driver and their outer ends being free. In the most desirable construction the teeth or projections are directed reversely to the direction of rotation, so that they in effect

constitute yielding cam projections adapted to ride over the diaphragm projection, to force the latter outward while themselves yielding toward the rotary body. In another embodiment the rotary part is provided with arms or projections, preferably of rigid or unyielding material, pivoted or otherwise loosely mounted on the driver and preferably held outward by means of springs in positions where their rotary path intersects the diaphragm or a projection thereon, these springs being preferably of such relative flexibility as to yield to greater or less extent at each driving contact of an arm with the diaphragm or with a wear piece thereon. Each of these rigid, loosely-mounted arms or projections are preferably constructed and arranged so that they assume a definite, supported position after each yielding driving contact. The provision of means for this purpose is of material advantage for several reasons, among others because thereby the arms may be held in positions where they will act upon the diaphragm to the greatest advantage, and will be prevented from swinging to a forward position where it might engage the diaphragm end on thereby avoiding danger of undue strain or rupture which may result where the forward swing of the pivoted member is not controlled or limited. In the form shown in the drawings, these arms will be acted on in greater or less degree by centrifugal force, which in this case will act in the same direction as the springs and will tend to hold them outwardly against thrust of the diaphragm. It will be obvious that with arms of sufficient mass the springs might be dispensed with, centrifugal force alone being relied upon to hold the arms in the extended operative position. In such a case, and wherever centrifugal force plays an important part in holding the projection in or throwing it out to operative position, the provision of stop means for limiting its movement is especially desirable, because it is thereby possible to fix the normal position of the arm so that its center of mass lies rearwardly of its pivot and in such case it is acted upon by centrifugal force with greater effect according as the center of mass is nearer the line of a tangent from the pivot and remote from the line of a radius passing through the pivot and the axis of the driver. In this

way, the arm will be held in position with sufficient force to deliver effective blows or forcing efforts to the diaphragm, though yielding and thereby cushioning the blows.

5 A further development of the invention includes means for first retracting or setting the arms on the rotary part by forcing them in against the action of the resilient cushioning member or material or against the action of centrifugal force, and then releasing them so as to permit them to fly outward and forward against the diaphragm or diaphragm projection, to deliver a blow at a speed which is a resultant of the velocity due to the angular movement of the carrier and the velocity due to centrifugal or spring movement of the released arm relative to its pivot. Such setting means may be employed in connection either with the projections of spring material or the rigid, spring-pressed arms. A simple construction utilizes a stationary setter having a cam surface which is eccentric to the rotary member, and so constructed as to gradually fold or force the arms backward, the end of this surface being properly related to the diaphragm or wear-piece so that the blow is delivered with the greatest force or from the most efficient direction. By 20 adjusting the setter so as to intercept the path of the arms to a greater or less extent, the amount and direction of the snap action may be correspondingly varied.

In the accompanying drawings illustrating certain of the possible embodiments of the invention: Figure 1 is a view of a complete signal, partly in side elevation and partly in section; Fig. 2 is a horizontal section through the rear part of the signal; 30 Fig. 3 is a similar view showing adjustable means for setting the spring projections; and Fig. 4 is a detail view showing a rotary driver provided with pivoted spring-sustained arms or projections.

45 The horn or resonator, 1, is carried by the front section 2 of the diaphragm case and the diaphragm 3 is held between cork washers or the like 4, 5 by the marginal clamping portions 6, 7 of the front section 2 and the rear section 8 of the diaphragm case. The clamping is effected by screws 9, which pass through openings in the clamping portions of the case sections and in the gaskets and the marginal region of the diaphragm. The 55 rear section 8 of the case is formed to receive a rotary driver 10, which is shown as a disk mounted on a rigid shaft 11, which is preferably substantially parallel to the diaphragm. This shaft is mounted and 60 rigidly held in the bearing 12, which may constitute a projection from the case 13 for inclosing the motor which is preferably a direct current rotary electric motor. The bearing sleeve 12 has external circular bearings 12^a and 12^b in the rear section 8 of the

diaphragm case, and the shaft is eccentric to these bearings, so that the actuator 10 may be adjusted to or from the diaphragm by rotary adjustment of the sleeve. If desired, other high speed means for rotating the driver may be employed.

70 The driver or rotary carrier 10 carries one or more actuating members 15, which are yieldingly sustained and coöperate with the diaphragm to effect bodily displacement thereof. In the simplest construction the said members 15 contact directly with the diaphragm or with a wear-piece 16 or other suitable thrust-receiving portion thereon. Preferably, the spring-sustaining means is 80 such that the contact members 15 yield at each thrust on the diaphragm. The members 15 may be themselves of elastic material so as to yield under the successive displacing efforts, or separate cushioning means may be provided, as illustratively shown in Fig. 4, where the members 15^a are preferably arms of unyielding material movably mounted on the driver, as by means of the pivots 16, and sustained by the springs 17. In the remaining views the spring-sustained projections are of resilient material, preferably of spring steel, though other material may be used. Preferably these projections of spring material are in the form of freely-projecting teeth, rigidly secured at their inner ends to the rotary carrier and free at their outer ends, so as to be capable of flexing throughout their length.

90 While it will be obvious that the members 15 or 15^a may be arranged in a variety of ways, it is considered preferable to mount them peripherally on the rotary actuating member. When they are formed as freely projecting arms or teeth as shown, they are 105 preferably directed contrary to the direction of rotation, but the distance to which they extend peripherally may be varied and in some constructions may be so shortened as to be negligible. As shown, the members 110 15 or 15^a in effect constitute yielding cams.

115 In the form of the invention shown in Fig. 4, where the projections are in the nature of rigid, or substantially rigid, pivoted arms, means are preferably provided for causing each of them to assume a definite position after yielding and delivering the driving impulse to the diaphragm. Stop means for the purpose may be of widely varying descriptions. I have shown the 120 arms as pivoted in peripheral recesses in the rotary carrier, the forward walls 30 of these recesses constituting stops for limiting the movement of the arms in the outward direction. The arms are held against these stops 125 by the action of the springs 17 or centrifugal force, or both. The stops are so arranged relatively to the arms that the latter are held with their centers of gravity materially in rear of the radius drawn through 130

the center of the rotary carrier and the pivot 16. It results, therefore, that centrifugal force may act with considerable effect on the arms. Moreover, whether the arms are held mainly by spring pressure or mainly by centrifugal force, these stops serve to prevent them from swinging too far forward thus preventing the possibility of endwise or too high angle impact of the arm upon the diaphragm, wearpiece or retractor 10 21, danger to the diaphragm being greatest where the retractor is omitted.

Fig. 3 shows one form of retractor or setting means which may be used for placing the rotor-carried spring projections 15 under elastic tension prior to releasing the same to deliver successive blows to the diaphragm. Where this is used, the diaphragm is actuated by impacts which are partly due to the rotary movement of the driver and partly to the spring action of the members 15 themselves. The construction and arrangement of the setting means may be widely varied and may be omitted if desired. In the illustrative form shown a stationary part 20 is provided with an eccentric contact surface 21 which intercepts the path of the peripheral members 15, so that these latter wipe over the contact surface to be gradually bent back until at the far end thereof they are permitted to snap into contact with the wear-piece 16. The extent of interception of the path of the spring teeth, as also the length of snapping movement executed thereby, may be varied by adjusting the eccentric member 20. This may be provided for in a great variety of ways. In the illustrative construction shown the member is provided with a curved slot 28 adapted to be adjustable by a pair of bolts 29 screwed in suitable holes in the case. By loosening the bolts, the member may be shifted and the bolts again tightened. A similar setting member 20 may be used in connection with the form of invention illustrated in Fig. 4, or it may be omitted. This member is so formed and positioned as to fold the arms gradually back on their pivots against the tension of the springs 17, the action of centrifugal force, or both, the forward end of the setting surface being at such distance in advance of the diaphragm wear-piece as to insure the delivery of the desired blow when each arm is carried around to the point where it escapes from this forward end of the cam surface. While the setting member has been shown comparatively short in Fig. 3, it will be obvious that it may be of any desired length, and may even be prolonged backward around the rotary member to a point where the arms will come under its influence soon after traveling past the diaphragm wear-piece. By prolonging the setting surface in this way, its eccentricity

may be very gradual, so that the arms are folded back in an exceedingly gentle manner, with minimum expenditure of power.

What I claim is:

1. In an alarm or signaling apparatus, a diaphragm, and mechanical means for actuating the same including a rotary driver, an actuating projection mounted yieldably thereon, a spring for causing the projection to assume striking position, and a stationary elongated setting surface intersecting the path of said projection and constructed to gradually retract the latter and to suddenly release it to deliver a blow to force the diaphragm. 75
2. In an alarm or signaling apparatus, a diaphragm, mechanical means for actuating the same including a rotary member having a yielding resiliently-sustained actuating portion, and elongated curved adjustable setting means for gradually retracting said portion and suddenly releasing it to deliver a blow to drive the diaphragm. 80
3. In an alarm or signaling apparatus, the combination of a diaphragm, a rotary member and means whereby the same is rotated at high speed, a pivoted arm carried by said member, and stop means for causing said arm to assume a definite position after each diaphragm-forcing effort. 90
4. In an alarm or signaling apparatus, the combination of a diaphragm, and a rotary member provided with a movable actuating arm pivoted thereon and a stop for limiting the outward or forward swinging movement of said arm. 100
5. In an alarm or signaling apparatus, the combination of a diaphragm, and rotary member provided with a pivoted actuating arm and stop means for limiting the outward movement of said arm so that its center of mass is considerably in rear of the radius from the axis of the rotary member to its pivot. 105
6. In an alarm or signaling device, a diaphragm, and a rotary member having a pivoted actuating arm arranged to vibrate the diaphragm, a stop for limiting the outward or forward movement of the arm, and a spring for urging the arm against said stop. 110
7. In an alarm or signaling apparatus, the combination of a diaphragm, a rotary member having a plurality of yielding diaphragm-actuating elements, and an elongated guide adjacent to said diaphragm, and in the path of said elements for placing said elements under elastic stress and releasing same to actuate the diaphragm, said guide being longitudinally adjustable to vary the releasing position of said elements in respect to said diaphragm. 120
8. An alarm or signaling device including a diaphragm having a wear-piece, a rotor mounted to rotate about an axis substantially parallel to said diaphragm, and hav- 130

ing a plurality of impact members pivoted thereto about the periphery and directed along said periphery contrary to the direction of rotation, and a separate spring connected with each impact member and tending to swing it in one direction about its pivotal connection with said rotor.

9. An alarm or signaling device including a diaphragm having a wear-piece, a rotor mounted to rotate about an axis substantially parallel to said diaphragm, and having a plurality of impact members pivoted thereto about the periphery and directed

along said periphery contrary to the direction of rotation, and a separate spring connected with each impact member and tending to swing the outer and rearward end thereof outwardly toward a radial position. ¹⁵
